CIGARETTE CASE

John L. Lebach, Forest Hills, N. Y.

Application October 9, 1948, Serial No. 53,657

10 Claims. (Cl. 206—41.2)

1

This invention relates to cigarette cases or carriers and is herein disclosed in some detail as embodied in a device adapted to hold the contents of a usual pack of cigarettes and adapted to project the cigarettes, one at a time, when desired, and to hold them well protected at other times.

In the form illustrated in some detail, the cigarettes or other cylindrical objects are adapted to be inserted in a swinging frame hinged so as to swing into and out of the open side of a casing.

The casing is shown as including a peripheral guide in which runs a band which normally overlies the upper ends of cigarettes. In the form shown the band is endless and is provided with two widely offset openings, so that the band may normally hold all the cigarettes within the case but is adapted to be slipped along to bring one or the other of the openings over the end of a cigarette with the result that a spring below the cigarette projects it through the opening to a point where it may be conveniently grasped.

Then the single cigarette may be withdrawn, and the other cigarettes remain held in place until the band is shifted and one of the openings releases a second cigarette.

In the form shown, the cigarettes are set in offset rows with the result that one opening in one reach of the belt may release successively the cigarettes of one row while the other opening may, at other times successively release the cigarettes of the other row.

In the form shown the band may be of metal and include ribs or corrugations which tend to hold it flat, and which may tend to spring into notches so that the bend tends to center the opening in alignment with any desired contained cigarette.

A full pack of cigarettes may be loaded, unloading requires no opening of case, which may be done with one hand holding the case. A slight thumb pressure works the release mechanism.

It will be found that this structure provides an easily assembled, strong, light, cheap and compact cigarette, or other case, capable of being made of numerous noble or other metals, and with built-in ornamented forms, if desired.

Other features and advantages will hereinafter appear.

In the accompanying drawings:

Fig. 1 is a side face view of one form of the invention showing a cigarette projected for seizing.

Fig. 2 is a plan view of the case of Fig. 1.

2

Fig. 3 is a similar view with the band in another position so that a cigarette is projected through the other opening in the band.

Fig. 4 is a sectional end view.

Fig. 5 is a sectional top view.

Fig. 6 is a perspective showing the cigarettes in the swinging frame ready to be closed.

Fig. 7 is an enlarged fragmentary side section of a corner showing the centering notches.

10 In the form shown cylindrical objects such as cigarettes 16 are inserted in the swinging rectangular frame 11 so that they fit between the guiding fingers 12 or short partitions 13, shown as corrugated metal ribbons attached at their ends 14, 15 to the flat metal outside plate 16 of the swinging frame 11.

The metal ribbon 17 ending at 15 is shown as attached directly to the end plate 18 of the frame 11, which in turn is attached to the outside plate 16, and the end plate 18 springs from the whole lower end (see Fig. 6) of the outside plate 16 and bends around parallel to the plate 16, and is corrugated at 19 to fit the outer curves of the outer row 20 of cigarettes.

25 It will be noted that the two rows of cigarettes 16, 20 (see Figs. 2, 5, 6) are staggered, with the result that the row 16 of cigarettes fits in the corrugation hollows on one side, and the other row 20 of cigarettes fits in the hollows on the opposite side of the ribbon 17.

In the form shown the swinging frame 11 turns on a long pintle 21 passing through ears 22 on the nearly rectangular casing frame 23, partly turned up along the lower outer edge at 44, said pintle also passing through bottom ears 45 turned up from the bottom of the plate 16. Thus the plate 16 and ribbon 17 and corrugated plate 18 turn and fit within the casing frame 23 so that the two rows of cigarettes 16 and 20 tend to move up to a broad movable band 24, since they are urged upward by individual light springs 25 that rest on the floor 26 formed by the flat bottom of the plate 18, where it bends horizontally to join the plate 16.

45 The frame 23 is able to guide the band 24 in a continuous groove 27 because the band also travels in an opposing continuous groove 28 in the opposite casing frame 29. The frame 29 preferably includes a thin plate 30 which closes the outside and serves to add to the stiffness of the structure and includes a boss 31 around its edge in which lies the groove 28.

The frame 23 is shown as held to the frame 29, 50 30 by a shouldered and headed rivet 32 at each

corner, thus making a strong, cheaply built structure.

In order to release the cigarettes one at a time, the band 24 is shown as provided with an opening 33 adapted to overlie any one of the cigarettes in one row. When the band 24 is pushed by the thumb, it releases the cigarette which it overlies and permits the spring 25 of that cigarette to thrust up a fraction of an inch as shown in Fig. 1, so that the cigarette may be readily withdrawn.

To insure that the opening 33 will be properly centered, the band 24 is shown as ribbed at 34 at spaced intervals equal to the distance between cigarette centers, and the ribs 34 are adapted to spring into shallow notches 35 at one corner 36 of the frames 23, 29 thus tending to center the opening 33 over the desired cigarette.

To release a cigarette in the other row 20, the band 24, at a point in the opposite reach of the band, is provided with a second cigarette release opening 37, so spaced relative to the ribs 34 that it tends to center over the desired cigarette of row 20 when a rib 34 seats itself in a notch 35.

Thus, the openings 33, 37 may be so placed in the band that when one is in a vertical reach of the device, the other opening is in the other vertical reach and all cigarettes are safely held.

The metal band 24 may be made continuous by soldering or welding its ends together and springs 25 may be each held in place by a drop of solder on the metal floor plate 26.

The cigarettes when inserted in the swinging frame 11 are held by light finger pressure, on their sides, if desired, against the urging of their springs 25.

In the form shown, the ribs 34 are V-shaped indentations with bottom openings 33 so narrow that one side or the other always overlies a cigarette beneath the band 24, and the corners of the casing frames 23, 29 are always on such a curve that band 24 may easily travel in the groove 27, and the groove is wide enough to accommodate the ribs 34, as the belt travels around within the casing periphery.

The total peripheral length of this band or belt is an aliquot multiple of distance between cigarette centers.

Having thus described one embodiment of the invention in some detail, what is claimed is:

1. In a holder for cylindrical objects, the combination with a swinging frame of fingers in the frame adapted to hold objects spaced therein, a spring for each object tending to thrust it forward in the fingers, a casing in which the frame turns to swing within the casing, a continuous belt adapted to overlie the objects swung within the casing and adapted to move peripherally and when so moved to bring an opening in it over a selected object so that the object is released and is lifted by its spring.

2. In a holder for cylindrical objects, the combination with a swinging frame of fingers in the frame adapted to hold objects spaced therein, a spring for each object tending to thrust it forward in the fingers, a casing in which the frame turns to swing within the casing, a continuous belt adapted to overlie the objects swung within the casing and adapted to move peripherally and when so moved to bring either of a pair of offset openings in it over a selected object so that the selected object is released and is lifted by its spring.

3. In a holder for cylindrical objects, the combination with a swinging frame of fingers in the

frame adapted to hold objects spaced therein, a spring for each object tending to thrust it forward in the fingers, a nearly rectangular casing on which the frame turns to swing within the casing, a nearly peripheral band forming part of the casing and having offset openings, a guide forming part of the casing on which the band slides so that one stretch overlies the objects when swung into the casing and adapted to bring the openings selectively to one or another of the objects.

4. In a holder for cylindrical objects, the combination with a swinging frame of fingers in the frame adapted to hold objects spaced therein, a spring for each object tending to thrust it forward in the fingers, a nearly rectangular casing on which the frame turns to swing within the casing and a nearly peripheral band forming part of the casing and having an opening adapted to be shifted by movement of the band to align with one or another of the objects when the objects have been swung into the casing.

5. In a holder for cylindrical objects, the combination with a swinging frame of fingers in the frame adapted to hold objects spaced therein, a spring for each object tending to thrust it forward in the fingers, a nearly rectangular casing on which the frame turns to swing within the casing, two facing frames forming part of the casing and including continuous facing slots, and a band including an object-passing opening slidable in the slots to bring the opening selectively over any of the objects.

6. In a holder for cylindrical objects, the combination with a swinging frame of fingers in the frame adapted to hold objects spaced therein, a spring for each object tending to thrust it forward in the fingers, a nearly rectangular casing on which the frame turns to swing within the casing, two facing frames forming part of the casing and including continuous facing slots and a band comprising ribs including an object-passing opening slidable in the slots to bring the opening selectively over any of the objects by centering it at notches opening off the slot.

7. In a holder for cylindrical objects, the combination with a swinging frame, of holding means in the frame for holding objects staggered in more than one line, a spring for each object urging it lengthwise out of its holding means, a casing on which the swinging frame turns to swing within the casing, a nearly peripheral band adapted to move around the casing and including an opening adapted to pass an object while the band holds other objects against their springs, and casing frames having slots within which the band travels to guide it.

8. In a holder for cylindrical objects, the combination with a pair of nearly rectangular frames forming a casing and having facing grooves, a swinging frame hinged to one of the rectangular frames and adapted to be swung within the casing, holding devices for the objects, a spring for each object urging it lengthwise, and a band running in said grooves having an opening adapted to permit one object to rise while holding others.

9. In a holder for cylindrical objects, the combination with a pair of nearly rectangular frames forming a casing and having facing grooves, a swinging frame hinged to one of the rectangular frames and adapted to be swung within the casing, holding devices for the objects, a spring for each object urging it lengthwise, and a band run-

ning in said grooves, having an opening adapted to permit one object to rise while holding others, and ribs on said band adapted to center the band at an object by seating in a notch in the groove.

10. In a holder for cylindrical objects, the combination with a pair of nearly rectangular frames forming a casing and having facing grooves, a swinging frame hinged to one of the rectangular frames and adapted to be swung within the cas-

ing, holding devices for the objects, a spring for each object urging it lengthwise and a band running in said grooves having offset openings to selectively permit one object to rise while holding others.
